(57) **CLAIM**

The ornamental design for an operation panel a for multifunction device as shown and described.

DESCRIPTION

FIG. 1 is a front view of an operation panel for a multifunction device showing our new design;

FIG. 2 is a rear view of the operation panel for the multifunction device;

FIG. 3 is a top view of the operation panel for the multifunction device;

FIG. 4 is a bottom view of the operation panel for the multifunction device;

FIG. 5 is a left view of the operation panel for the multifunction device;

FIG. 6 is a right view of the operation panel for the multifunction device; and,

FIG. 7 is an enlarged view of the operation panel for the multifunction device along lines 7-7 shown in FIG. 4 showing a translucent part, in which the gray-colored part is the translucent part.

In FIGS. 1, 4, and 7, the color gray represents translucency. The dash-dot broken lines represent portions of the article that form no part of the claimed design. The dash-dot-dot broken lines represent the bounds of the enlarged views and form no part of the claimed design.

1 Claim, 7 Drawing Sheets
